US00D753483S

(12) **United States Design Patent**
Accursi

(10) **Patent No.:** **US D753,483 S**
(45) **Date of Patent:** **** Apr. 12, 2016**

(54) **CAPSULE USED IN THE PREPARATION OF A BEVERAGE**

(71) Applicant: **CAFFITALY SYSTEM S.P.A.**, Gaggio Montano (Bologna) (IT)

(72) Inventor: **Giovanni Accursi**, Porretta Terme (IT)

(73) Assignee: **CAFFITALY SYSTEM S.P.A.**, Gaggio Montano (IT)

(**) Term: **14 Years**

(21) Appl. No.: **29/501,208**

(22) Filed: **Sep. 2, 2014**

(30) **Foreign Application Priority Data**

Mar. 6, 2014 (EM) 002419432-0001

(51) **LOC (10) Cl.** **09-03**

(52) **U.S. Cl.**

USPC **D9/429**

(58) **Field of Classification Search**

USPC D9/414, 416, 418, 419, 423, 424, 425, D9/428, 434, 435, 438, 440, 447, 454, 499, D9/442, 444, 500, 501, 502, 503, 504, 505, D9/535, 544, 696, 715, 716, 733, 777; D7/387, 400, 399, 229/906.1, 405; 220/359.2; 206/216, 5, 222, 217, 548, 206/528, 532, 530; D3/202; 426/77, 80, 426/115, 122

(57) **CLAIM**

The ornamental design for a capsule used in the preparation of a beverage, as shown and described.

DESCRIPTION

FIG. 1 is a perspective view of a capsule used in the preparation of a beverage, showing my new design;

FIG. 2 is a front elevational view thereof, the back elevational view, right side elevational view and left side elevational view being identical thereto;

FIG. 3 is a top plan view thereof; and,

FIG. 4 is a bottom plan view thereof.

1 Claim, 2 Drawing Sheets
